Specification of Letters Patent.

Patented Dec. 23, 1913.

Application filed February 2, 1909. Serial No. 475,628.

To all whom it may concern:

Be it known that I, GEORGE F. WATT, a citizen of the United States of America, residing at Harrisburg, in the county of 5 Dauphin and State of Pennsylvania, have invented certain new and useful Improvements in Tally Attachments for Type-Writing Machines, of which the following is a specification.

10 My present invention relates generally to typewriting machines, but specifically to what is known as a tally attachment designed to facilitate the making of a tally record of certain data, as for instance the 15 debit and credit totals of bills, statements, and the like.

The invention is a further development of the idea involved in Patent No. 846,671 to King and Milstead and in the co-pending 20 application for patent of Joram Ziegler No. 388,785. In the King and Milstead patent is disclosed a flat platen or book typewriter characterized by a stationary flat platen over which is disposed a machine frame 25 movable longitudinally of the platen to line space the writing, which is accomplished by downwardly acting printing mechanism mounted on a carriage which travels transversely of the platen on the machine frame 30 to letter space the writing. To this machine the tally attachment is applied. It consists of front and rear carriers for the tally strip or web wound upon and extended between the carriers and having its intermediate portion 35 extended under the machine frame and disposed above the platen and over that portion of the bill, statement, or other work sheet upon which the debit and credit totals or other data is printed. By reason of this 40 relation the totals are printed on the tally strip and are transferred to the subjacent bill, a tally record of the totals being thus secured as the bills are typewritten by the machine. The unused tally is fed forward 45 from the rear carrier and wound upon the front carrier by the action of the line spacing mechanism which advances the machine frame step-by-step lengthwise of the platen and the completed tally record is removed 50 from the machine by unwinding the printed portion of the tally from the front support of the carrier.

In the Ziegler application the King and Milstead structure was improved upon by 55 providing the tally strip with line spacing

mechanism distinct from that of the typewriter, but so arranged that while the operation of the machine line spacing mechanism would not effect the feeding of the tally strip, the operation of the tally line 60 spacing mechanism would effect the line spacing movement of both the tally strip and the machine. This arrangement avoided the wasteful feeding of the tally strip during the printing of the body of the bill, 65 but insured proper line spacing of the tally strip and machine after the entry of the bill totals on the strip.

A further development which characterized the Ziegler construction was a novel arrangement of the tally carriers which made it possible to locate the tally strip at different points widthwise of the platen and to more readily remove the printed tally record from the machine. These results, however, 75 were only obtainable by what now appears to be a very cumbersome and time-consuming adjustment of the parts.

The object of my invention, stated generally, is to produce an improved construction 80 embodying all of the desirable characteristics of both the King and Milstead and Ziegler constructions and adapted to effect the same ends with greater facility and additional ends by simple and efficient means. 85

More specifically, one object of the invention is to provide means whereby the tally strip may be readily shifted into and out of operative position thus eliminating the necessity for entirely removing the tally strip 90 or for tearing away that portion which lies opposite the platen, in the manner which has heretofore been customary, when it is not desired to secure a tally record of any portion of the matter printed. 95

To the accomplishment of this end the invention consists in providing the machine with front and rear tally carriers adjustable to dispose the tally strip at the desired point and shiftable in unison into and out of its operative position. 100

A further object is to provide for the feeding of the tally strip from front to rear so that the numbers printed thereon will appear in sequence from top to bottom instead of having their natural order reversed, as heretofore, it being understood that when the tally is fed from rear to front, as in the earlier constructions above referred to, the last entry appears at the top of the tally rec- 110

ord instead of occupying its natural position at the bottom thereof. This object is accomplished by providing tally line spacing mechanism including an actuator mounted at the front of the machine frame and arranged to operate, through intermediate mechanism, the rear tally carrier which in this instance constitutes one of a pair of feed rolls between which the rear end of the tally strip is fed from a supply roll mounted on the front carrier.

A still further object is to provide means facilitating the detachment of the printed portion of the tally strip. To this end the rear end of the strip is fed back over a paper table from the feeding rolls and under a cutter across, which the extended rear end of the tally record may be drawn and severed when desired.

Another object is to provide means facilitating the renewal of the supply roll. To this end the tally roll is removably mounted in the frame at the front of the machine by slipping the roll over a spindle mounted in open bearings in the frame and held in place by a spring-urged plate, serving both as a guard plate and as a tension device for the roll, one of the tally feeding rolls at the rear of the machine being mounted in a movable journal frame by means of which the feed rolls may be separated when desired to facilitate the threading of the rear end of the tally strip.

Subordinate to the various objects stated are others which will hereinafter appear as the succeeding description of the illustrated embodiment of the invention is developed.

In the accompanying drawings—Figure 1 is a plan view of a portion of an Elliott-Fisher typewriter equipped with my tally attachment, the tally being shown out of use or in its inoperative position in full lines and the operative position of the tally strip being indicated by dotted lines. Fig. 2 is a front elevation of the same subject-matter with the tally strip moved over somewhat from the position shown in Fig. 1. Fig. 3 is a rear elevation of the subject-matter of Fig. 2. Fig. 4 is an end elevation of the machine equipped with my invention, old and well-known parts of the typewriting machine being omitted. Fig. 5 is a sectional view showing the relation of the tally strip, and its supports and guides, to the frame of the typewriter. Fig. 6 is a sectional view through the line spacing mechanism. Fig. 7 is a detail view of the primary bearing plate. Fig. 8 is a detail view of the two secondary bearing plates. Fig. 9 is a detail view of that portion of the tally line spacing mechanism which is directly associated with the feed rolls. Fig. 10 is a detail view showing the connection between the tally line space lever and the adjacent element of the tally line spacing mechanism.

Fig. 11 is a detail perspective view of the front tally frame with the tally roll in place. Fig. 12 is a similar view of the rear tally frame showing the manner in which the rear end of the tally strip is detached. Fig. 13 is a side elevation of the rear tally frame, showing the journal frame in normal position and indicating in dotted lines the position to which the frame is moved for the purpose of separating the feed rolls, and Fig. 14 is a detail perspective view of one end of the primary feed roll.

Each part wherever shown is indicated by a reference character appropriated to it.

1 indicates the stationary flat platen of the Elliott-Fisher billing machine or typewriter. Longitudinally of this platen extend tracks 2 upon which travels the machine frame 3 movable longitudinally to line space the typewriting accomplished by key-operated printing mechanism 4 mounted on the carriage 5 movable transversely of the platen on the frame 3 to letter space the writing.

As is well understood in the art, the carriage 5 is propelled by spring drums and is controlled by the usual key-operated escapement mechanism. A disclosure of the escapement mechanism is not necessary for the purposes of this invention, but the drums are indicated by 6 in Figs. 2 and 3. The printing mechanism is downwardly acting and the work sheet, as for instance a bill or the like, is supported in a flat, spread-out condition on the platen, as indicated at a in Fig. 3.

The main frame 3 of the machine is advanced step-by-step over the platen by line spacing mechanism which includes a spacing shaft 7 extending across the front of the frame 3 and carrying pinions 8 which mesh with the toothed tracks 2. The shaft 7 is afforded bearings in brackets 9, 10 and 11 secured to the front of the frame 3. The brackets 10 and 11 are located adjacent to the right hand end of the shaft and between them the shaft is provided with a knurled wheel 12 fixed to the shaft and a rocker arm 13 loose on said shaft 7.

A line spacing lever or actuator 14 is pivoted at the free end of the rocker arm 13 and is arranged to engage the knurled wheel 12 to rotate the same and thus rotate the pinions 8 for the purpose of causing the machine to travel along the tracks 2 the distance of one line space when the actuator 14 is drawn forward. Forward movement of the actuator is limited by a stop 15 projecting from the bracket 10, see Fig. 2, and a retracting spring 16 serves to retract the rocker arm 13 and actuator 14 after each line spacing operation. The throw of the line spacing lever or actuator 14, and thus the extent of the line space movement of the machine is regulated by a

variable stop mechanism 17 which limits the return movement of the lever.

The line spacing mechanism described is that ordinarily employed on the Fisher type of Elliott-Fisher machines and is exemplified in Patent No. 703,954 issued to R. J. Fisher, July 1, 1902, to which reference is made for a more specific disclosure than is considered necessary for the present purpose.

The tally attachment.—What is known as the tally attachment is provision whereby a comparatively narrow strip of paper known as the tally sheet or strip is carried by the machine frame and extended between the writing surface and the printing mechanism and imposed above the right hand margin of a bill. The under side of the tally strip is carbonized, usually with two contrasting colors, as for instance red and black, in longitudinal stripes or bands and when the debit and credit totals of the bill are printed, the printing point of the machine is above the tally strip so that these totals are printed on the strip and are transferred to the subjacent bill. By this means a tally record of debit and credit totals is made simultaneously with the making out of the bills. At the end of the day, or any other period, the printed portion of the tally strip is removed and constitutes a tally or check for the billing accomplished within the period named.

In the constructions already proposed two objectionable characteristics have been noted, as heretofore premised. One of these objections has been that the tally has been fed forwardly so that the last entry has appeared at the top of the strip instead of at the bottom, and the second objection has been the necessity for either completely removing the attachment from the machine or for tearing away a portion of the tally strip when a tally record is not desired.

The mechanism to be described has been designed with special reference to overcoming the two primary objections noted as well as others of a subordinate character. The tally strip 18 is led over the platen and under the machine frame from a supply roll 19 mounted in front of the frame and its rear end is passed between a pair of feed rolls 21 and 22 located in rear of the frame, see Fig. 5. The roll 19 is supported upon a core or carrier 23 having extended ends or trunnions 24 which are afforded bearings in open-ended slots 25 in the vertical side members 26 of what may be termed the front tally frame 27. The front tally frame 27 comprises the two side members or plates 26 and a transverse horizontal plate 28 connecting the side plates at their lower edges and constituting a tally guide under which the tally is led close above the writing surface of the platen from the roll 19, the

front edge of the plate or guide 28 being curved upwardly, as indicated at 29, to avoid an abrupt angle in the tally strip.

The front tally frame 27 is provided with a combined cover plate and tension member 30 hinged to the side members 26, as indicated at 31, and normally drawn down upon the upper surface of the roll 19 by a spring 32. The lower end of the spring 32 is secured to the bottom plate 28 of the frame 27 and its upper end is secured to the combined cover and tension plate 30 at a point in advance of the axis of the latter when said plate 30 is in its normal or depressed position. The spring 32 thus acts to draw down the plate 30 with sufficient force to cause the latter to act as a tension device or brake for the supply roll of the tally strip, but when the plate 30 is elevated to the position shown in dotted lines in Fig. 5, the point of connection between the spring and plate will lie in a plane in rear of the axis of the plate, which will thus be held in elevated position. The spring 32 will thus be seen to hold the plate in either position to which the plate is moved by hand.

Adjacent to the lower rear corners of the side plates 26 are formed openings 33 for the reception of a bar 34 extended across the front of the frame and secured thereto at its opposite ends by brackets 35, see Figs. 2 and 8. The bracket plates 35 are interposed between the main frame 3 and the brackets 9 and 10, and are secured by the screws utilized to retain said brackets. The bar 34 constitutes a guide for the front tally frame which latter is shiftable along said rod in a direction transverse to the platen for the purpose of disposing the tally strip in or out of its operative position.

The tally feeding rolls 21 and 22 are mounted in a rear tally frame 36 comprising side plates 37 and a bottom plate 38, the latter being slotted, as indicated at 39, to accommodate the tally strip which passes upwardly through said slot to the feed rolls 21 and 22. The front end of the bottom plate 38 is extended forwardly beyond the side plates 37 and is carried down and under the rear bottom bar of the frame 3 to constitute the upper member 40 of the rear tally guide 41, the lower member or plate 42 of which is secured at its rear end to the bottom wall 38 in rear of the slot 39 and has its front end extended horizontally to a point considerably in advance of the front edge of the upper member 40 of the guide. The plate 42 thus supports that part of the horizontal portion of the tally strip which extends rearwardly from the printing point of the machine and also acts as a guard to prevent the tally strip from contacting with the edge of a primary work sheet when the machine frame is moved rearwardly over the platen.

To facilitate the threading of the tally between the feed rolls a curved guide plate 43 is extended upwardly and rearwardly from the front edge of the slot 39 in the bottom plate of the rear tally frame. Thus if the rear end of the tally strip is passed into the rear guide 41 it is guided upwardly to the slot 39 by the curved portion of the plate 42 and its advancing edge is then caught by the plate 43 and directed to the pass between the upper and lower feed rolls 21 and 22.

In rear of the feed rolls is disposed a rearwardly extended and slightly upwardly inclined paper table 44 in the form of a metal plate having an angular front end carried under and secured to the bottom plate 38 of the frame 36. The table 44, which may be termed the tally table, supports the printed portion of the tally above the platen and carries it a sufficient distance in rear of the machine to prevent the loose rear end of the tally from being caught under the machine as the latter is moved back and forth in the act of billing.

The upper or secondary feed roll 22 is provided with trunnions 45 resting within upwardly opening bearing slots 46 in the side plates 37 and to these trunnions are secured springs 47 having their lower ends secured to the walls 36, see Figs. 12 and 13. The springs 47 draw the roll 22 downwardly or toward the primary feed roll 21 and thus yieldingly retain the two rolls in proper frictional contact with the tally strip to insure the proper feeding of the latter as the rolls are rotated by mechanism to be described.

It is desirable to effect a separation of the rolls 21 and 22 to facilitate the initial threading of the tally strip, as well as to permit a considerable portion of the tally strip to be drawn rearwardly by hand and independently of the tally feeding mechanism when desired. This end is accomplished by what may be termed a feed roll adjusting frame 48 of approximately inverted U-shape to provide end plates 49 pivotally attached at 50 to the side plates 37 and a cross bar 51 connecting the side plates and equipped with a finger piece or handle 52 by means of which the frame 48 may be swung to either of two positions indicated in Fig. 13.

In the normal position of the frame 48, shown in full lines in Fig. 13, the trunnions 45 of the upper feed roll 22 are received by notches or rests 53 in the upper edges of the side plates 49 and thus prevent swinging movement of the frame 48. In advance of the notches or rests 53 and disposed in a somewhat higher plane are other notches or seats 54 formed in the upper edges of the plates 49. It will be seen, therefore, that if the frame 48 is swung back from the posi-

tion shown in full lines in Fig. 13 to the position indicated in dotted lines in said figure, the trunnions 45 of the upper feed roll 22 will be elevated or cammed up into the higher notches 54, the springs 47 opposing a yielding resistance to this elevation of the roll 22 and also serving through the medium of the trunnions 45 to retain the frame 48 in its new position. Thus when the roll adjusting frame 48 is in its forward or normal position, shown in full lines in Fig. 13, the two feed rolls will be in co-operative relation to feed the tally strip. On the contrary, if the frame 48 is thrown back to the position indicated in dotted lines in Fig. 13, the upper feed roll will be elevated and the feed rolls thus separated to facilitate the threading of the tally strip between the rolls or the rearward withdrawal of a considerable portion of the tally strip by hand.

To facilitate the severance of the printed portion of the tally strip, the rear edge of the cross bar 51 of the roll adjusting frame 48 is beveled or sharpened to form a cutter 55 along which the tally strip may be drawn, as indicated in Fig. 12. The rear tally frame 36, like the front tally frame 27, is designed to be shifted laterally and for this reason a guide bar 56, similar to the bar 34, is extended across the rear side of the frame 3 of the typewriter and secured in any suitable manner, as for instance to plates 57 secured to foot brackets 58 which are commonly secured to the back of the typewriter frame and engage the tracks 2, see Figs. 1 and 3. The bar 56 thus constitutes a guide bar for the rear tally frame, being accommodated by openings 59 in the side walls of the latter.

The tally feeding mechanism.—The tally strip is fed step by step in the direction of line spacing by what may be termed a tally line space actuator 60 in the form of a lever mounted to swing from an extension 61 of the bracket 11, see Fig. 6, and retracted by a spring 62 secured at one end to the bracket and at its opposite end to the lever, as best shown in Fig. 2. As it is desirable that the machine be line spaced or advanced with reference to the primary work sheet simultaneously with the feeding of the tally strip past the printing point of the machine, the actuator 60 is provided as in the Ziegler application, heretofore mentioned, with a laterally disposed arm 63 which causes the machine line space actuator 14 to be operated whenever the tally line space actuator 60 is operated, but as the arm 63 is located behind the lever 14, it will of course be understood that the machine line spacing mechanism can be operated without feeding or line spacing the tally strip. This relation of the machine line spacing mechanism and the tally line spacing mechanism is

desirable because the machine must be frequently line spaced with reference to the primary work sheet or tally, as the statement on the latter is made out, whereas it is only necessary to line space the tally strip after each entry of bill totals.

While the relative arrangement of the two line space actuators 14 and 60, shown in the accompanying drawings, is substantially that of the two actuators of the Ziegler construction, the mechanism operated by the tally actuator 60 is entirely unlike that heretofore proposed and constitutes one of the features of my invention. In the present instance the tally is fed rearwardly, as heretofore stated, by the rotation of the feed rolls 21 and 22 and in order to effect this result it is simply necessary to provide a suitable connection between the actuator 60 and the primary feed roll 21 to cause the necessary movement of the latter whenever the actuator is oscillated. To attain this end the roll 21 which, like the roll 22, is faced with rubber or other suitable material, is splined on a shaft 64 afforded bearings in the plates 57 and extended entirely through the plate at the right hand side of the machine (the left hand side of Fig. 3) and through the adjacent foot bracket 58. At its right hand extremity the shaft 64 is provided with a knurled head 65 by means of which the shaft and the primary feed roll 21 may be turned freely by hand. Adjacent to the head 65 a ratchet wheel 66 is fixed to the shaft 64, see Figs. 3 and 9, and between this ratchet wheel and the head 65 a pawl carrier 67 is mounted to swing loosely on the shaft and carries a pawl 68 designed to engage the ratchet, as shown in Fig. 9, and to rotate the latter and the primary feed roll one increment or step when the carrier 67 is oscillated.

The outer end of the carrier 67 is connected by a link 69 to an arm 70 extended from one end of a rock shaft 71 afforded bearings in flanges 72 and 73 bent rearwardly from a bearing plate 74 screwed to the rear side of the main machine frame 3. At its opposite, or outer end the shaft 71 is provided with a second arm 75 connected by a link 76 to the arm 77 of a rock shaft 78 located at the front side of the machine and afforded bearings in the flanges of a bearing plate 79 secured to the front of the main machine frame 3. At its opposite or inner end the shaft 78, see Fig. 2, is provided with an arm 80 bifurcated for the reception of a pin 81 extending laterally from the rearwardly disposed short arm 82 of the tally line space actuator 60. Thus it will be noted that when the actuator 60 is drawn forward the shaft 78 will be rocked and a similar rocking motion will be communicated through the link 76 to the rear rock shaft 71 which, through the medium

of the arm 70 and the link 69, will swing the pawl carrier 67 rearwardly, see Fig. 9, and thus cause the pawl 68 by engagement with the rack 66 to rotate the shaft 64 and the primary feed roll 21. When the actuator 60 is released it is restored to normal position by the spring 62 and simultaneously the pawl 68 is drawn back to engage the next tooth of the ratchet 66 preparatory to a repetition of the tally feeding operation.

As heretofore stated, when the actuator 60 is operated to rotate the primary feed roll and thus feed the tally rearwardly, the arm 63, extending from the actuator 60, will engage and operate the actuator 14 of the machine line spacing mechanism to effect a forward feed of the machine to the next line space of the primary work sheet. In other words, the operation of the tally line space actuator 60 will effect simultaneously a rearward feed of the tally sheet and a forward feed of the traveling printing mechanism so that the printing mechanism will drop down to the next lower line space of the stationary primary work sheet while the feed of the tally sheet will present the next lower line space thereof opposite the printing point. The machine and the tally strip move in opposite directions, but the same result is effected by each movement, as in either case the next lower line space of the sheet, whether the primary sheet or the tally strip, is presented in position for the reception of the next entry.

Attention is directed to the somewhat indirect connection between the actuator 60 and the primary feed roll 61. This indirect connection is necessitated by the fact that the carriage of the typewriter travels from end to end of the frame 3 and it is therefore necessary that the connections of the tally feeding mechanism be carried around the end of the machine frame so that the link 76 for instance will not interfere with the printing mechanism when the carriage is moved a sufficient distance to the right to print at a point adjacent to the right hand side of the platen.

The means for shifting the tally into and out of operative position.—It has been explained that the front and rear tally frames 27 and 36 are adjustable transversely of the platen along the bars 34 and 56; the line space shaft 7, which passes through the front frame, and the shaft 64, which passes through the rear frame, also serving to assist in the supporting and guiding of these frames in their lateral movement. By reason of this lateral shifting of the tally supports it is possible to shift the tally into and out of a predetermined operative position, since it will be seen that if, when the tally strip occupies the position indicated in dotted lines in Fig. 1, it overlies the total columns of the bills or primary work sheet

it may be shifted to the right to an inoperative position beyond such total columns, this latter or inoperative position being indicated by the full line position of the tally 5 in said figure.

In some cases the structure as thus far described may be sufficient for all practical purposes, since the tally frames may be shifted independently to the desired positions and thus secured either by their own frictional engagement with the guide rods or by any other approved provision for their retention. I prefer, however, to connect the front and rear tally frames in a manner to 10 insure their lateral movement in unison so that under all conditions they will be in accurate alinement with the intervening portion of the tally extending parallel with the tracks 2.

20 Since it is not desirable to have the frame connecting means extend over the platen where it might possibly be struck by the printing mechanism, I prefer to provide front and rear rack bars 83 and 84, see Figs. 1, 2 and 3, secured at their inner or left hand ends to the front and rear tally frames and provided at their outer ends with toothed racks 85 engaging pinions 86 mounted at the opposite ends of a shaft 87, see Fig. 1, afforded bearings in the outer or right hand ends of the plates 74 and 79. By this means, to-wit the rack bars 83 and 84, the pinions 86 and the shaft 87, corresponding lateral movement of the front and rear tally frames 25 is insured by connecting mechanism so located as to oppose no obstruction in the path of the typewriter carriage as the latter travels from end to end of the machine frame 3 and similarly opposes no obstruction between the printing mechanism and the platen.

Since the normal position of the tally strip may vary, the two tally frames are adjustably connected to the rack bars 83 45 and 84 by means of set screws 88 screwed into collars 89 integral with or fixed to the tally frames and encircling the cylindrical inner ends of the bars 83 and 84. In order to insure the location of the frames in corresponding positions relative to the two rack bars, the latter may be provided with corresponding indications, as for instance notches 90, or any other desired form of graduation.

55 The manner of mounting and guiding the rack bars may be varied within wide limits, but preferably the rear bar 84 is passed through and afforded a bearing in the flange 72 of the plate 74 and said plate is provided 60 with a headed stud 91 which acts as a guide for the rack bar immediately above the adjacent pinion 86.

To insure the accurate positioning of the tally strip, when shifted quickly into or out 65 of operative position, I mount upon one of

the rack bars, preferably the rear rack bar 84, a pair of adjustable stops 93 and 94 which by contacting with the flange 72 of the plate 74 limit the lateral movement of the tally strip in opposite directions. Since the two tally frames are connected, the tally may be readily shifted by exerting slight pressure upon one side or the other of the front tally frame, but I prefer to mount a knurled thumb wheel 95 on the front end of the shaft 87, see Figs. 1 and 2. By rotating this thumb wheel in one direction or the other, the shaft 87 is correspondingly rotated and the pinions 86 engaging the rack bars 83 and 84 shift the latter longitudinally and thereby shift the tally frames to present the tally strip either in or out of position for use.

It will be noted that while the rack bars 83 and 84 and the shaft 87, together with the pinions 86, constitute connecting means for the front and rear tally frames, these elements also constitute a tally shifting mechanism whereby the rear tally frame is shifted when the front frame is moved by hand or whereby both frames are simultaneously shifted a corresponding distance when the thumb wheel 95 is rotated by the operator.

It is thought that from the foregoing, the construction and operation of the tally attachment and the means whereby the several stated objects of the invention are accomplished will be clearly understood, but while the construction illustrated and described is thought at this time to be preferable, I reserve the right to effect such variations of the illustrated structure as may come fairly within the scope of the protection prayed.

What I claim is:—

1. The combination with a typewriting machine including a platen and printing mechanism, of a tally attachment including means for supporting the tally strip in operative position, and means for shifting the tally strip supporting means relative to the platen and transversely of the strip.

2. The combination with a typewriting machine including a platen and printing mechanism, of a tally attachment including means for supporting the tally strip in position to be written upon, and means for shifting said supporting means to move the tally strip laterally to a different position relative to the platen.

3. The combination with a platen and printing mechanism, of a tally attachment including strip supporting means, means for feeding the strip endwise, and means for shifting said strip supporting means transversely of the strip and relative to the platen.

4. The combination with a platen and printing mechanism, of a tally attachment

including a pair of frames laterally shiftable to displace the tally from the printing position, and tally strip carriers mounted in the frames, said carriers being movable to permit endwise movement of the strip supported thereby.

5. The combination with a platen and printing mechanism, of a pair of supporting frames shiftable relative to the platen parallel with the lines of writing, carriers mounted in the frames to support the paper strip in position to be printed upon, means connecting the frames to compel the same to move together, and means for effecting a line space feed of the strip.

6. The combination with a platen and printing mechanism, of a pair of supporting frames shiftable relative to the platen parallel with the lines of writing, carriers mounted in the frames to support a paper strip in position to be printed upon, means for shifting the frames, and means for feeding the paper strip endwise.

7. The combination with a platen and printing mechanism, of a pair of supporting frames shiftable relative to the platen, rotary paper supports mounted in the frames, and means for rotating one of the rotary paper supports to effect the line space feed of a paper strip extended between said supports.

8. The combination with a platen and printing mechanism, of a pair of frames shiftable parallel to the lines of writing and relative to the platen, means for compelling the frames to move in unison, rotary paper supports mounted in the frames, and means for rotating one of the supports to effect the line space advance of a paper strip extending between the supports.

9. The combination with a platen and printing mechanism, of a pair of shiftable paper supports, and means for shifting said supports, said means including a shaft and rack and pinion mechanism between said shaft and the paper supports.

10. The combination with a platen and printing mechanism, of a pair of paper supports, and mechanism connecting the supports and movable therewith; the connection between the supports and said connecting mechanism being adjustable.

11. The combination with a platen and printing mechanism, of a pair of paper supports, rack bars adjustably connected to the supports, a shaft, and pinions mounted on the shaft and engaging the rack bars.

12. The combination with a platen and printing mechanism, of paper supports between which a strip of paper is adapted to be extended, said supports being shiftable parallel to the lines of writing, and adjustable means for limiting the shifting movement of said supports.

13. The combination with a platen and

printing mechanism, of a pair of shiftable paper supports, bars extended from the supports and shiftable therewith, means for compelling the bars to move in unison, and coacting stops for limiting the movement of the bars.

14. The combination with a stationary platen adapted to support a primary work sheet, of printing mechanism movable over the platen to line space the writing on said primary work sheet, a secondary work sheet movable with the printing mechanism in the line space advance of the latter, and means for effecting a line space advance of the secondary work sheet in a direction opposite to the line space advance of the printing mechanism.

15. The combination with a stationary platen and printing mechanism movable thereover, of a tally attachment including front and rear tally carriers movable with the printing mechanism and adapted to support a work sheet extended between said carriers, and means for feeding the tally sheet rearwardly.

16. The combination with a typewriter including a platen, a movable frame and printing mechanism mounted on the frame, of a tally attachment including means for supporting a tally strip extending from front to rear, and means for simultaneously moving the frame forwardly and the tally strip rearwardly.

17. The combination with a platen and printing mechanism movable thereover, of a tally attachment including means for supporting a tally strip in position to be printed upon by the printing mechanism, means for advancing the printing mechanism relative to the platen and for simultaneously moving the tally strip rearwardly relative to the printing mechanism, and means for advancing the printing mechanism without effecting the rearward movement of the tally strip.

18. The combination with a platen and printing mechanism, of a tally attachment including means for supporting a tally strip in position to be printed upon, and line spacing mechanism including two actuators, one of said actuators being operative to advance the printing mechanism and the other of said actuators being operative to effect a simultaneous forward movement of the printing mechanism and rearward movement of the tally strip relative to the printing mechanism.

19. The combination with a typewriting machine including a frame, printing mechanism, and a platen, of a tally attachment including a pair of laterally shiftable tally frames, a tally roll mounted in one frame, feed rolls mounted in the other frame, and means for operating the feed rolls to withdraw the tally strip from the tally roll.

20. The combination with a typewriting machine, of a tally attachment including connected laterally shiftable frames, a tally roll mounted in one frame, feed rolls mounted in the other frame, and means for operating a feed roll to effect line spacing movement of a tally strip led between the feed rolls from the tally roll.

21. The combination with a typewriting machine including a platen, printing mechanism and line spacing mechanism, of a tally attachment including tally supporting means engaging the tally at different points in the length thereof with the intermediate portion of the tally disposed opposite the writing line of the platen, and mechanism operative to shift the tally supporting means relative to the platen and in a direction parallel to the lines of writing to displace the tally laterally from a predetermined position.

22. The combination with a typewriting machine, including a stationary platen, a machine frame movable thereover, and printing mechanism carried by the frame, of a tally attachment including front and rear carriers supported by the frame in front and rear thereof to sustain a tally strip led under the printing mechanism, and tally shifting mechanism carried by the frame and operative to shift the tally laterally into and out of position for use.

23. The combination with a typewriter, including a frame, platen and printing mechanism, of a tally attachment, supported

exclusively by the frame and including front and rear tally carriers, means for supporting said carriers from the frame, and shifting mechanism operative to shift the carriers to displace the tally strip from normal position.

24. The combination with a typewriting machine, including a frame, carriage, a printing mechanism, of a tally attachment mounted exclusively on the frame of the typewriter and including front and rear tally carriers between which a tally strip is led, said carriers being movable in unison to shift the tally strip transversely, and shifting mechanism operative to shift the carriers.

25. The combination with a typewriting machine including a stationary platen, frame movable longitudinally thereof, a carriage movable on the frame and printing mechanism on the carriage, of a tally attachment including front and rear tally carriers mounted on the frame to support a tally strip extended between the carriers and movable over the platen with the frame, and means including an actuator located at the front of the typewriter frame and operative to effect a rearward feed of the tally strip relative to the frame.

In testimony whereof I affix my signature in presence of two witnesses.

GEORGE F. WATT.
